UNITED STATES PATENT OFFICE.

JOHN McLACHLAN, OF CHICAGO, ILLINOIS.

PAVING-BLOCK.

SPECIFICATION forming part of Letters Patent No. 681,248, dated August 27, 1901.

Application filed December 17, 1894. Serial No. 532,012. (No model.)

To all whom it may concern:

Be it known that I, JOHN McLACHLAN, a citizen of the United States, residing at Chicago, in the county of Cook and State of Illinois, have invented certain Improvements in Paving-Blocks, of which the following is a specification.

My invention relates to pavements, particularly such as are designed to be put down in cities where there is great wear and where noise is to be avoided as much as possible. In such cases it is desirable to have a block which is light in weight, which tends to resist moisture, which is slightly elastic and, so far as possible, noiseless, and which can be readily shaped and made of proper size to work in its desired position. I am referring, of course, to block-pavements such as are commonly made in public thoroughfares by wood, stone, tile, metal, or other such blocks.

I will first describe the drawings whereby I have illustrated my invention.

Figure 1 is a plan view of a section of a street. Fig. 2 is a cross-section through the same.

Like parts are indicated by the same letters throughout the drawings.

A A are blocks of suitable size and shape and resting upon the base, bottom, or support B. This bottom or base may rest upon the soil or upon a concrete or prepared bed C, and where rails D D of a street-car line are used the ties E E should be embedded in the concrete or soil and the rails be secured thereto. These blocks consist of a fibrous material of natural growth, such as wood or the like, the fiber of which has not been broken, but which remains in substantially its natural condition save that the fibers have been compressed to an enormous degree, so that they are flattened or forced into close or intimate contact with each other without separation or disintegration. Moreover, during a portion of the period during which such blocks are being so formed or compressed or in a portion of the process through which they are passed prior to such compression I force into the pores of such wood or fibrous material a quantity of oil or the like substance. The substance, therefore, of which I form the blocks has as its "base" or "starting-point," so to speak, the natural wood; but it

is reduced or changed from this natural condition by a process in which there is incorporated with it a quantity of oil or the like to resist the effect of moisture, and the fibers of the wood are compressed or forced together, so as to make an exceedingly firm close-grained product. These blocks are forced into the proper form, size, or shape, but can be subsequently cut or split, and when placed in position I prefer to have the ends of the fiber turned upwardly. These blocks are, as indicated, suitably placed upon a proper base and are brought up at the sides against proper side supports, as the street curb, rail of street-car line, &c. A suitable packing or filling can be placed about and between or beneath the blocks. Such a block is comparatively noiseless, is not slippery, as is the case with some other kinds of blocks, has enormous wearing capacity, is light in weight, and powerfully resists the action of moisture, rain, snow, and the like.

The process of compression of course expresses from the fibrous material the albuminous and other such substances.

The filling or substance between the blocks may be of soft wood or the like. For example, it may be boards suitably treated to prevent their absorption of moisture, but so as to permit them to have a certain capacity to give. The insertion between the blocks which is made according to my invention will have a very firm surface and is preferably of some material, at least, which will give and can be indented, so as to prevent horses and the like slipping.

A feature of my pavement to which I wish to call attention is that although the blocks are made of wood they are of such a nature as to prevent the absorption by them of moisture and the like, and hence do not have the bad sanitary effect of many such blocks. They can also be impregnated with "Sanitas oil" or other disinfecting substances which are known to possess germ-killing properties.

The blocks herein referred to are compressed with the fiber in its natural arrangement and charged with moisture-proof substance, the blocks being given a permanent set, so as to retain their compressed shape without the aid of holding devices. These blocks are held in a fixed relation to each

other by any desired means, so as to form a substantially even upper surface.

I claim—

1. A pavement for streets, consisting of a base and side supports, a series of blocks of highly-compressed fibrous material, the fiber in its natural arrangement and charged with moisture-proof substance, said blocks compressed before being associated together and given a permanent set so as to remain compressed without confining devices, and a holding device for holding said blocks in a fixed relation to each other, so that their upper surfaces form a substantially level pavement, said holding device having no tendency to compress the blocks when the holding device and blocks are brought together, substantially as described.

2. A pavement for streets, consisting of a suitable base and side supports, a series of compressed oil-saturated blocks, said blocks consisting of highly-compressed fibrous material, the fiber in its natural arrangement, the softer or albuminous materials being forced from the wood and the fibers being given a permanent set so that the blocks retain their density and shape without retaining devices, a holding device for holding the blocks in a fixed relation to each other, said holding device having no tendency to compress the blocks when the holding device and blocks are brought together.

JOHN McLACHLAN.
